COMBINED BOTTLE AND EYE CUP

Charles E. Akers, 201 N. Wells St., Park Ridge, Ill.

Filed May 29, 1961, Ser. No. 65,391

Term of patent 14 years

(Cl. D58—6)

FIG. 2 is an end elevational view taken from the right of FIGURE 1;

I claim:

The ornamental design for a combined bottle and eye cup, as shown.
